 Regulator Company, Chicago, Ill., a corpora-
 tion of Illinois

Application February 28, 1945, Serial No. 580,261

12 Claims. (Cl. 175—363)

1

The invention relates generally to electrical control circuits and more particularly to control circuits wherein a small signal is utilized to govern substantially larger power applications, or where the signal is amplified or modified, or both, for subsequent use in its amplified and/or modified form.

Heretofore circuits of the character described have depended largely upon electron tubes for accomplishment of the ends sought, necessitating complicated circuits or excessive numbers of stages of amplification with the resultant disadvantages of high cost, operational and maintenance difficulties and, above all, the disadvantage that the controlling portion of the circuit was not completely independent of the controlled portion so that reaction in the controlled portion might reflect into the controlling portion with possible resultant injury thereto.

It is an object of this invention, therefore, to provide new and improved circuits for the amplification or modification, or both, of a signal, or for the utilization of a small signal in the control of substantially larger power applications.

Another object of the invention is to provide new and improved electrical control circuits adaptable to respond either to alternating current or direct current signals and adaptable to produce either direct or alternating current.

Another object is to provide new and improved electrical control circuits in which the input or controlling circuit is completely separated electrically from the output or controlled circuit and cannot be influenced by the output circuit.

Another object is to provide a circuit of the character described having a portion operating as a large range amplification stage which is without electron tubes.

Another object is to provide a circuit of the character described having an electron tubeless, main amplification or control stage and an input signal circuit in advance of the main stage conditioning the signal by modification and possibly also amplification for use in connection with the main stage.

Still another object is to provide a control circuit in which the main amplification and control means is composed of saturable reactors.

A further object is to provide a control circuit including saturable reactors which will function as a stable and linear direct current power amplifier, or as a linear amplifier and converter of D. C. signals to alternating current.

Still a further object is to provide a control circuit including saturable reactors which will

2

function as a stable and linear alternating current power amplifier, or as a linear amplifier and converter of A. C. signals to direct current.

Other objects and advantages will become apparent from the following detailed description taken in connection with the accompanying drawings, in which:

Fig. 1 is a box-type diagrammatic illustration of a circuit embodying the features of this invention.

Fig. 2 is a circuit diagram illustrating in detail a possible construction that the units represented by the rectangles in Fig. 1 may take.

Fig. 3 is a diagram illustrating the character of the output of the first unit of the circuit.

Fig. 4 is a diagram similar to Fig. 3 illustrating the character of the output of the second unit of the circuit.

Fig. 5 is a diagram similar to Fig. 3 illustrating the character of the final output of the circuit.

Fig. 6 is a box-type circuit diagram showing a modified embodiment of the invention.

Fig. 7 is a circuit diagram illustrating a specific form that the units represented by the rectangles of Fig. 6 may take.

Fig. 8 is a circuit diagram illustrating another specific form that the units represented by the rectangles of Fig. 1 may take.

Fig. 9 is a diagram illustrating the character of the output of the first unit of Fig. 8.

Fig. 10 is a diagram similar to Fig. 9 illustrating the character of the output of the second unit of Fig. 8.

Fig. 11 is a diagram similar to Fig. 9 illustrating the character of the output of the third or final unit of Fig. 8.

For purposes of disclosure there is shown in the drawings and will hereinafter be described a general and several specific circuits, being illustrative embodiments of the invention. It is not intended, however, that the invention is to be limited thereby to the specific disclosures made. On the contrary, it is intended to cover all modifications and alternative constructions falling within the spirit and scope of the invention as defined in the appended claims.

Generally speaking, the invention contemplates the provision of a new and improved circuit wherein a small electrical signal is utilized to govern substantially larger power applications or where the signal is amplified or modified, possibly both, for subsequent use in its new form. In such a circuit the input is a controlling signal while the output is a controlled signal regardless of whether the latter is of a magnitude commonly

referred to as a signal or is of such magnitude as to be, or is in fact, the operating energy for an electrical device such as a motor or the like. To that end, the circuit is composed generally of means for modifying and possibly amplifying the controlling or the controlled signal, and means functioning as the main amplifying or control means.

Herein the general circuit (see Fig. 1) is composed of three subcircuits or circuit units or portions A, B and C. Of these units, A is the main amplifying or control means or circuit and functions to have an output of alternating current controlled as to magnitude and sign by the controlling or input signal, but having an independent power source so that the power output is not limited by the power of the signal source. Unit B is the control signal receiving unit. This unit usually functions to amplify the signal but, above all, it modifies the character of the signal so as first to obtain a signal of a character suitable for use with unit A, and, secondly, to obtain a signal of such character as to result in an output of a character desired. Unit C is also a modifier of the signal which it receives, though herein the function of unit C is always that of a rectifier converting the A. C. output of unit A to a D. C. output. The term "direct current" or its abbreviation D. C., as herein employed to designate the output of the units C and B and the control coils of the unit A, is used in the broad sense of that term, i. e., as opposed to alternating current and as including pulsating current such as produced by a generator or rectifier and not in the limited sense only of absolutely continuous, pulse-free current such as produced by a chemical cell under constant load.

As the description proceeds, it will become apparent that by appropriate construction of the unit B and by use or elimination of the unit C the invention may be employed to respond either to an A. C. or a D. C. input or control signal, while obtaining either an A. C. or a D. C. output. Moreover, by the employment of A. C. or D. C. signal receiving units B of the character hereinafter described, circuits embodying the concept of this invention may be employed to obtain an A. C. output which is directly proportional in magnitude to the magnitude of the input signal regardless of whether that be an A. C. or a D. C. signal; and similarly a D. C. output may be obtained which also is proportional to the input signal regardless of whether the same is an A. C. or a D. C. signal. Equally important is the fact that the sign of the output, be it the A. C. output or the D. C. output, is also controlled by the sign of the input or control signal. The meaning of the term "sign" as applied to D. C. signals or output is, of course, the customary meaning and hence will be understood. The meaning of the term "sign" as applied to an A. C. signal or output is that of 180° phase displacement. Thus circuits embodying the concept of this invention may be employed as D. C. amplifiers, as amplifiers and converters of A. C. signals to D. C. signals, as means for controlling A. C. output either by D. C. or A. C. signals, or, as stated another way, as an amplifier of A. C. signals and as an amplifier and converter of D. C. signals into A. C. signals or output.

Turning now to a consideration of the more detailed embodiments of the invention, the unit A, being the basic portion of this invention, will first be described. This unit, as already stated, is the main amplification stage and control

unit or subcircuit and accomplishes control of the magnitude and the sign of the output in accordance with the magnitude and sign of the signal without the employment of electron tubes. 5 The unit A is the same in all of the circuits disclosed herein and it will thus be described in detail but once in connection with the description of the circuit disclosed in Fig. 2. Referring to Fig. 2, the unit A comprises a pair of saturable reactors represented by the broken-line rectangles 15 and 16. The saturable reactor 15 is composed of a pair of A. C. coils 17 and 18 and of a D. C. coil 19 serving as the control coil. All of the coils are wound on a common iron core 20 in such manner that current flowing in the coils 17 and 18 will not induce current or voltage in the D. C. coil 19, while flux produced by direct current flowing in the D. C. coil 19 will vary the impedance of the A. C. coils 17 and 18 by varying the degree of saturation of the core 20. The reactor is further so designed that the coils 17 and 18 have a very high impedance when no current is flowing in the D. C. coil 19. Necessarily the reactor and particularly the coils thereon must be designed with a view to the voltages with which it is to be employed, with the coils 17 and 18 being capable of taking substantially the full applied voltage when no current is flowing in the D. C. coil 19. The saturable reactor 16 is identical with the reactor 15 and comprises A. C. coils 21 and 22 and a D. C. coil 23, all wound on a common iron core 24.

The unit A, hereinafter sometimes referred to as the saturable reactor circuit, is completed by an A. C. supply circuit comprising power supply leads 25 and 26 adapted to be connected to an A. C. power source represented at 27, and output leads 28 and 29 terminating in output terminals 30. The A. C. coils of the saturable reactors are so connected in the supply circuit that the output will have a sign depending upon which of the two reactors is predominating at the time, while the magnitude of the output is determined by the extent of energization of the D. C. coil of the predominating reactor. In other words, the A. C. coils of the saturable reactors are so connected in the supply circuit that when one of the reactors is predominating the output terminals 30 will be connected to the source 27 in one manner, while when the other reactor is predominating the connection of the output terminals 30 to the source 27 will just be reversed, thereby bringing about the reversal in sign above mentioned. While this might be accomplished in a variety of ways, the A. C. coils 17 and 21 have one end connected to the power lead 25 by leads 31 and 32, respectively. The coils 18 and 22 of the reactors 15 and 16, respectively, have one end connected to the power lead 26 by leads 33 and 34, respectively. The remaining ends of the coils 17 and 21 are by leads 35 and 36 connected, respectively, to the output leads 28 and 29, while the remaining ends of coils 18 and 22 are by leads 37 and 38 connected, respectively, to the output leads 29 and 28. This results in effect a construction in which the coils 17, 18, 21 and 22 form the legs of a Wheatstone bridge with the power supply leads 25 and 26 being common to the coils 17 and 21 and 18 and 22, respectively, and with the output leads 28 and 29 in common to the coils 17 and 22 and 18 and 21, respectively.

In the embodiment of the invention shown in Fig. 2, the circuit is adapted to respond to a D. C. input or control signal. Accordingly, there

is illustrated, by way of example, a unit B which is operable to receive a D. C. signal, amplify the same to a magnitude suitable for use in connection with the saturable reactors 15 and 16 and, at the same time, cause energization of one or the other, or both, of the D. C. windings 19 and 23, as may be desired. Herein the unit B is of such character that an input signal will cause energization of the D. C. windings 19 and 23, as shown in Fig. 3, wherein the line i_1 represents the current flowing in the coil 19 and i_2 represents the current flowing in the coil 23. In other words, when the input signal is zero the coils 19 and 23 will each have the same current flowing therein with a value as represented by the crossing of the lines i_1 and i_2 at the point 40. With an increase in the signal magnitude, the current in the coil 19 will increase, while the current in the coil 23 will decrease at the same rate. Upon reversal of the sign of the signal and increase in magnitude, the current in the coil 23 will increase while the current in the coil 19 will decrease again at the same rate.

While a unit B capable of producing currents in the coils 19 and 23 of the character described might take a variety of forms, one such unit is shown in Fig. 2, it being understood that the showing is exemplary only and that a variety of other subcircuits might be employed and that, in particular, it might prove necessary to have more than one stage to produce the amplification of the signal required to provide direct currents of a magnitude suitable for control of saturable reactors. Herein the unit B or signal input circuit comprises a pair of electron tubes 43 and 44 each having a plate 45, a cathode 46 and a grid 47. The tube 43 has a plate circuit, generally designated 48, which includes the D. C. coil 19 of the saturable reactor 15 and the tube 44 has a plate circuit, generally designated 49, which includes the D. C. coil 23 of the saturable reactor 16. A D. C. voltage source, herein shown as a battery 50 common to the two plate circuits 48 and 49, supplies the plate voltage of the tubes. Each of the tubes 43 and 44 has a grid circuit, generally designated 51 and 52, respectively, with each circuit including a resistance 53 and a grid bias voltage source, here shown as a battery 54 common to the two grid circuits. The D. C. signal input terminals 55 and 56 are connected to the not common ends of the resistances 53. As above indicated, the tubes 43 and 44 are normally so biased that at zero magnitude of input signal an equal current will flow in the plate circuits of the tubes. As the signal increases in magnitude from zero value, the current in the plate circuit of one of the tubes will increase, while the current in the plate circuit of the other of the tubes will decrease proportionately depending upon the sign or polarity of the input signal.

For ready understanding of this invention, the operation of the circuit as thus far described will now be set forth. Let it be assumed, therefore, that the input signal is zero. Under this assumption, the direct current flowing in the coils 19 and 23 will be equal and, while such flow of current in the windings 19 and 23 will serve to reduce the impedance of the A. C. coils of the saturable reactors, nevertheless, there will be no difference in potential across the output terminals 30 of the saturable reactor circuit. This is due to the fact that the output terminals 30 are through leads 28 and 29 connected to points in the energy supply circuit which are at the same potential. Let

it next be assumed that the sign or polarity of the D. C. input signal is such that an increase in signal magnitude falls to the right of the vertical axis of the graph of Fig. 3. Under those circumstances the current i_1 flowing in the D. C. coil 19 will increase and the current i_2 flowing in the coil 23 will decrease, such increase and decrease being by equal amounts and proportional to the increase in signal input. With such increased flow of current in the coil 19, the impedance of the A. C. coils 17 and 18 associated therewith will decrease and there will be a correspondingly smaller voltage drop across those coils. Oppositely, with a decrease in the current flowing in the D. C. coil 23, the impedance of the coils 21 and 22 of the reactor 16 will increase and there will be an increased voltage drop across those coils. As a result, with the A. C. coils connected as here shown, there will be a difference of potential between the output terminals 30. The magnitude of this difference of potential between the output terminals 30 will vary proportionally with the D. C. input signal, for variation in the currents i_1 and i_2 is proportional to the input signal as can readily be seen from Fig. 3. The absolute value of the output of the saturable reactor circuit is, however, not limited by the absolute value of the input signal. On the contrary, this absolute value of the output of the saturable reactor circuit will be determined by the character and size of the A. C. supply source 27.

If now it be assumed that the sign or polarity of the input signal is reversed and then increases in magnitude as before, it will be noted that just the opposite occurs, that is, that the current i_2 flowing in the coil 23 increases, whereas the current i_1 flowing in the coil 19 decreases again by proportional amounts. This time the impedance of the coils 21 and 22 of the reactor 16 is decreased while the impedance of the coils 17 and 18 of the reactor 15 is increased. This again produces a difference of potential between the output terminals 30. This potential, however, is of the opposite sign or polarity from that obtained from the condition above assumed, though for equal input signal magnitudes the magnitude of the A. C. output of the saturable reactor circuit will be the same. As a consequence, there results a circuit having, as best seen in Fig. 4, an alternating current output represented by the line 56 which is proportional in magnitude to the magnitude of a D. C. input signal and which corresponds in sign to the sign or polarity of the D. C. input signal. Thus the circuit of Fig. 2 so far described gives control by means of a D. C. signal over the power supplied to a single phase A. C. load, with the control governing not only the magnitude but also the phase or sign of the A. C. power supplied, and with the magnitude of the supply proportional to the magnitude of the D. C. signal. In this connection, it is also pointed out that, with the A. C. coils of the saturable reactors so connected as to prevent their inducing any voltage in the associated D. C. coil, the saturable reactor circuit is incapable of influencing the signal input circuit and thus reactions of the controlled signal, that is, the output of the saturable reactor circuit, be it of a character to be classified as a signal, or be it the actual power supplied to a load, such as a motor or the like, cannot be reflected back into the signal input circuit.

In the embodiment of the invention shown in Fig. 2, the unit C is connected as the A. C. load

of the saturable reactor circuit. Herein, as already stated, the unit C is a rectifier and, as a result of the employment of a rectifier which gives full wave rectified output, a circuit results which is in effect a direct current amplifier. Herein the rectifier unit C is composed of four grid controlled, gaseous tubes 60, 61, 62 and 63, each having a plate 64, a cathode 65 and a grid 66. The rectifier is inductively coupled to the saturable reactor circuit through the medium of a transformer T having a primary winding 67 connected to the output terminals 30 and a secondary winding 68. The tubes 60 to 63 are connected to operate in pairs, depending upon the polarity of the output of the saturable reactor circuit. To that end, the plates 64 of the tubes 60 and 61 are by leads 69 and 70, respectively, connected to the ends of the secondary winding 68, while the cathodes 65 of the tubes 62 and 63 are by the same leads connected to the ends of the secondary winding 68. The cathodes 65 of the tubes 60 and 61 in turn and the plates 64 of the tubes 62 and 63 are by a common lead 71 connected to a center-tap 72 of the secondary winding 68. The lead 71 actually, of course, is a split lead incorporating therein output terminals 73 to which a D. C. load is intended to be connected. The grid voltages are designed to be either in phase or in counterphase with the output of the saturable reactor circuit, so that one or the other of the pairs of tubes may function, depending upon the sign or phase of the output of the saturable reactor circuit. Accordingly, the grids 66 of the tubes 60 and 61 are by leads 74 and 75, respectively, connected to the ends of a secondary winding 76 of a transformer 77 having a primary winding 78 adapted to be connected to a suitable A. C. source represented at 79. The midpoint of the secondary winding 76 is by a lead 80 connected to the common lead 71. Potential for the grids 66 of the tubes 62 and 63 is provided respectively by windings 81 and 82 constituting a split secondary of a transformer 83 having a primary winding 84 connected to a suitable A. C. source represented at 85. The remaining ends of the windings 81 and 82 are connected, respectively, to the leads 69 and 70. It is to be appreciated that, though not here shown, suitable heating elements are provided for the cathodes of the tubes.

With a rectifier of the character here disclosed, one of the tubes 60 to 63 will fire during each half cycle of the alternating current output of the saturable reactor circuit. Tubes 60 and 61 will fire, one for the positive, the other for the negative full half cycle when the output of the saturable reactor has one sign, while the tubes 62 and 63 will fire, one for the positive, the other for the negative half cycle when the output of the saturable reactor circuit is of reversed sign. Thus full wave rectified output is obtained at the output terminals 73 of the rectifier circuit. Since full wave rectified output is obtained, it will be proportional in magnitude to the magnitude of the output of the saturable reactor circuit and hence proportional to the magnitude of the input signal since the output of the saturable reactor circuit (see Fig. 4) was shown to be proportional to the input signal. Further, the D. C. output of the rectifier circuit will vary in polarity with the polarity of the input signal and thus there results an output such as represented by the line 86 of Fig. 5, namely, a D. C. output which is proportional in magnitude to the magnitude of the

input signal and also corresponding in sign to the sign of the input signal.

The complete circuit of Fig. 2 lends itself to the employment of a negative feed-back, thereby assuring a stable and linear D. C. amplifier. To that end, a potentiometer, generally designated 87, is connected across the output terminals 73 of the rectifier circuit with the end terminal 88, and the variable terminal or contact 89 by leads 90 and 91, respectively, connected into the input circuit intermediate the terminal 85 and the resistance 63 in such manner as to serve as a negative feed-back.

In Figs. 6 and 11, inclusive, there are disclosed 15 embodiments of my invention in circuits responding to or controlled by an A. C. signal. Such circuits may have an A. C. output, as in Figs. 6 and 7, or may have a D. C. output, as in Fig. 8. Referring first to Figs. 6 and 7, the circuit therein 20 disclosed is composed of a saturable reactor circuit A' and an input signal amplifying and modifying unit or subcircuit B'. The saturable reactor circuit or the unit A' is identical with the unit A shown in Fig. 2. Suffice it to say, therefore, that the unit A' is composed of two saturable reactors 15' and 16' and that the reactor 15' has two A. C. coils 17' and 18' and a D. C. coil 19', and that the reactor 16' has two A. C. coils 21' and 22' and a D. C. coil 23'. Completing 30 the saturable reactor circuit is a supply circuit having power leads 25' and 26' connected to a source of alternating current power, represented at 27', and output leads 28' and 29' connected to output terminals 30'. The coils are connected as described in connection with Fig. 2.

Unit B', the signal input circuit, like the unit B of Fig. 2, is adapted to receive the input or control signal, amplify it so as to convert it to a value capable of use with saturable reactors, 40 and modify or condition the signal for use with saturable reactors and to accomplish the end here sought. Such modification in this form of the invention involves conversion of the signal from A. C. to D. C. and further involves modification to result in a signal of appropriate character. Herein the unit B' must be such as to result in a current in the D. C. windings 19' and 23' of the character illustrated in Fig. 9. In other words if i_1' represents the current flowing in the winding 19' and i_2' represents the current flowing in the winding 23', the currents in the windings 19' and 23' at zero value of input signal must be equal and must have a value such as represented by the point 40' at which the line representing the current i_1' and the line representing the current i_2' cross in the graph of Fig. 9. It will be seen from this figure that as the signal increases in value from zero the current in one of the D. C. windings will increase, while the current in the other D. C. winding will decrease, the increase and decrease being proportional to one another and also proportional to the increase in signal magnitude. Depending upon the sign of the input signal, one or the other of the coils 55 19' and 23' will have the current flow therein increased, while the other will have the current flow therein decreased.

Shown in Fig. 7 for exemplary purposes only, it being understood that a variety of other circuits might be employed and that, in particular, it might be necessary to provide more than a single amplification stage, is one specific embodiment that the unit B' may take. As shown in 75 Fig. 7, unit B' comprises a pair of electron tubes

101 and 102, each having a plate 103, a cathode 104 and a grid 105. The tube 101 has a plate circuit, generally designated 106, having in series therein, in parallel with a condenser 107, the D. C. coil 19' of the saturable reactor 15'. The tube 102 has a plate circuit, generally designated 108, which has connected in series therein, again in parallel with a condenser 109, the D. C. coil 23' of the saturable reactor 16'. The plate circuits of the tubes 101 and 102 are completed by an A. C. voltage source, represented at 110, common to the two plate circuits and providing the plate voltage for the tubes. The grids 105 are connected to opposite ends of a winding 111 constituting the secondary winding of a transformer, generally designated 112, having a primary winding 113 connected at its ends to signal input terminals 114 and 115. The midpoint of the secondary winding 111 is by lead 116 connected to the juncture of the plate circuits with the cathodes. Though not here shown, it is to be appreciated that the tubes 101 and 102 are provided with suitable means for heating the cathodes 104.

The tubes are normally biased so that at zero signal magnitude there is flow of current in the plate circuit of the tubes and, moreover, this current is equal in the two plate circuits. With such bias and with the circuit arranged as here shown, an increase in magnitude of the A. C. signal from zero value will result in an increase in the plate current of one of the tubes and a corresponding decrease in the plate current of the other tubes. Whether the plate current of the tube increases or decreases with an increase in signal value is determined by the sign of the A. C. input signal.

A brief description of the operation of the circuit of Figs. 6 and 7 may facilitate understanding of the invention and appreciation of the advantages thereof. Let it be assumed, therefore, that the input signal is zero. Under that condition, there will flow in the D. C. coils 19' and 23' a direct current of the same value. While there is thus current flowing in the D. C. coils 19' and 23', with a resultant change in the impedance of the A. C. coils, there is no difference of potential between the output terminals 30' because the terminals 30', due to the particular arrangement of the A. C. coils in the supply circuit, are connected to points in the circuit having the same potential. Let it be assumed further that the A. C. input signal is now increased from zero to some definite magnitude and that the sign of the input signal is such that the signal will lie to the right of the vertical axis of the graph of Fig. 9. Under that assumption, the current i_1' flowing in the D. C. winding 19' will increase, while the current i_2' flowing in the winding 23' will decrease. Hence the degree to which the cores of the saturable reactors 15' and 16' are saturated with flux will be varied with a resultant change in the impedance of the A. C. windings of the reactor 15' and the A. C. windings of the reactor 16'. This will, due to the manner of connection of the A. C. coils in the supply circuit, produce a voltage differential between the output terminals 30'. Conversely, if the sign of the input signal is reversed and the signal then increased in magnitude as before, the current i_2' flowing in the D. C. winding 23' will increase, while the current i_1' flowing in the winding 19' will decrease. Hence the voltage differential between the terminals 30' will be of the same value as previously described, but the sign of the output voltage will be the reverse of that described for the previous condition. It will be apparent,

therefore, that there will be obtained an output of the character represented by the line 117 of Fig. 10, namely, an output which is proportional in magnitude to the input signal and which, moreover, varies in sign with the sign of the input signal.

It will be seen from the foregoing that the circuit of Figs. 6 and 7 may be considered as an A. C. amplifier. To assure a stable and linear A. C. power amplifier, a negative feed-back is preferably incorporated and the circuit of Figs. 6 and 7 lends itself admirably to this purpose. Accordingly, there is connected across the output terminals 30' a potentiometer, generally designated 118. The fixed terminal 119 and the movable contact 120 of this potentiometer are by leads 121 and 122, respectively, connected into the input circuit intermediate the input terminal 115 and the primary winding 113 in a manner to provide a negative feed-back.

In Fig. 8, there is disclosed an embodiment of the invention wherein an A. C. input signal results in an amplified D. C. output which is proportional in magnitude to the magnitude of the input signal and which, moreover, has a sign or polarity corresponding to the sign of the A. C. input signal. To that end, a rectifier circuit or unit C' is connected as the load of the saturable reactor circuit or unit A' which, in turn, is controlled by an input signal circuit or unit B', the latter two being the corresponding units of Figs. 6 and 7. The unit C' is identical with the unit C of Fig. 4. Suffice it to say, therefore, that the rectifier C' comprises four grid controlled, gaseous electron tubes 60', 61', 62' and 63', each tube having a plate 64', a cathode 65' and a grid 66'. The rectifier C' is inductively coupled to the saturable reactor circuit A' through the medium of a transformer T' having a primary winding 67' connected to the output terminals 30' of the saturable reactor circuit and a secondary winding 68'. Plate voltages are obtained by connection of the plates of the tubes 60' to 63' to the ends of midpoints of the secondary winding 68', while grid voltages are obtained from suitable A. C. sources represented at 79' and 88' with the grid voltages either in phase or in counter-phase with the output of the saturable reactor circuit A'. The tubes are so connected that they operate in pairs, one pair functioning when the output of the saturable reactor circuit is of one sign, the other pair functioning when the output of the saturable reactor circuit is of reversed sign, with one tube firing during each half cycle so as to obtain full wave rectification.

With this full wave rectification, the D. C. output of the circuit will be proportional in magnitude to the A. C. output of the saturable reactor circuit and, inasmuch as this latter output has already been shown to be proportional to the magnitude of the A. C. signal (see Fig. 10), the D. C. or end output of the entire circuit will also be proportional in magnitude to the A. C. input signal. Further, with the sign of the output of each unit corresponding and controlled by the sign of the input to each unit, the D. C. or end output of the entire circuit will also correspond to the sign of the A. C. input signal. Accordingly, there results an output of the character represented by the line 123 of Fig. 11.

I claim as my invention:

- An electrical control circuit comprising a signal input circuit having two sets of output terminals and operable to produce at each set of output terminals a direct current which at

zero signal is equal at both sets of terminals and is above zero in magnitude and upon increase in signal magnitude increases in magnitude at one set of terminals and decreases correspondingly at the other set of terminals, increase or decrease of the output current at a set of terminals being dependent upon the sign of the signal, a saturable reactor circuit comprising a pair of saturable reactors each having a pair of A. C. coils and a control coil wound on a common core, the A. C. coils being so arranged as not to induce an A. C. voltage in the associated control coil and said control coils being connected one to each set of output terminals of said input circuit, and a supply circuit for an A. C. load adapted for connection to a source of alternating current, the A. C. coils of said reactors being connected in the supply circuit to form with the load separate circuits each including the A. C. coils of one reactor reversely connecting the load in said supply circuit, and a full wave rectifier circuit connected to form the load for said supply circuit and having output terminals for the connection of a D. C. load thereto, the output of said rectifier circuit varying in sign and magnitude with the input signal.

2. An electrical control circuit comprising a signal input circuit having two sets of output terminals and operable to produce at each set of output terminals a direct current which at zero signal is equal at both sets of terminals and is above zero in magnitude and upon increase in signal magnitude increases in magnitude at one set of terminals and decreases correspondingly at the other set of terminals, increase or decrease of the output current at a set of terminals being dependent upon the sign of the signal, a saturable reactor circuit comprising a pair of saturable reactors each having a pair of A. C. coils and a control coil wound on a common core, the A. C. coils being so arranged as not to induce an A. C. voltage in the associated control coil and said control coils being connected one to each set of output terminals of said input circuit, and a supply circuit for an A. C. load adapted for connection to a source of alternating current, the four A. C. coils of said reactors being connected in the supply circuit in a manner such that each forms one leg of a Wheatstone bridge, and that the A. C. coils of each reactor form diametrically opposed legs of the bridge, and a full wave rectifier circuit connected to form the load for said supply circuit and having output terminals for the connection of a D. C. load thereto, the output of said rectifier circuit varying in sign and magnitude with the input signal.

3. An electrical control circuit comprising a signal input circuit having two sets of output terminals and operable to produce at each set of output terminals a direct current which at zero signal is equal at both sets of terminals and is above zero in magnitude and upon increase in signal magnitude increases in magnitude at one set of terminals and decreases correspondingly at the other set of terminals, increase or decrease of the output current at a set of terminals being dependent upon the sign of the signal, a saturable reactor circuit comprising a pair of saturable reactors each having a pair of A. C. windings and a D. C. winding wound on a common core, the A. C. windings being so arranged as not to induce an A. C. voltage in the associated D. C. winding and said D. C. windings being connected one to each set of output terminals of said input circuit, and a supply circuit for an A. C. load

adapted for connection to a source of alternating current, the four A. C. coils of said reactors being connected in the supply circuit in a manner such that each forms one leg of a Wheatstone bridge, and that the A. C. coils of each reactor are in series when there is an unbalance of the bridge, and a rectifier circuit comprising an inductive coupling having a primary winding connected as the load in said supply circuit and a center-tapped secondary winding, two pairs of grid controlled, gaseous electron tubes, one pair of said tubes having its plates connected to the ends of said secondary winding and its cathodes connected to the center-tap on said secondary, and the other pair having its plates connected to the center-tap and the cathodes connected to the ends of said secondary winding, and means providing grid voltages for said tubes keeping the grid voltages of one pair of tubes in phase and the grid voltages of the other pair of tubes in counterphase with their respective plate voltages.

4. In an electrical control circuit, a signal input circuit having two sets of output terminals and operable to produce at each set of output terminals a direct current which at zero signal is equal at both sets of terminals and is above zero in magnitude and upon increase in signal magnitude increases in magnitude at one set of terminals and decreases correspondingly at the other set of terminals, increase or decrease of the output current at a set of terminals being dependent upon the sign of the signal, and a saturable reactor circuit comprising a pair of saturable reactors each having a pair of A. C. coils and a D. C. coil wound on a common core, the A. C. coils being so arranged as not to induce an A. C. voltage in the associated D. C. coils and said D. C. coils being connected one to each set of output terminals of said input circuit, and a supply circuit for an A. C. load adapted for connection to a source of alternating current, the four A. C. coils of said reactors being connected in the supply circuit in a manner such that each forms one leg of a Wheatstone bridge and that the A. C. coils of each reactor are connected in diametrically opposed legs of the bridge.

5. An electrical control circuit comprising a D. C. signal input circuit having two sets of output terminals and operable to produce at each set of output terminals a direct current which at zero signal is equal at both sets of terminals and is above zero in magnitude, and upon increase in signal magnitude increases in magnitude at one set of terminals and decreases correspondingly at the other set of terminals, increase or decrease of the output current at a set of terminals being dependent upon the sign of the signal, a saturable reactor circuit comprising a pair of saturable reactors each having a pair of A. C. coils and a D. C. coil wound on a common core, the A. C. coils being so arranged as not to induce an A. C. voltage in the associated D. C. coil and said D. C. coils being connected one to each set of output terminals of said input circuit, and a supply circuit for an A. C. load adapted for connection to a source of alternating current, the A. C. coils of said reactors being connected in the supply circuit to form with the load separate circuits each including the A. C. coils of one reactor reversely connecting the load in said supply circuit, and a full wave rectifier circuit connected to form the load for said supply circuit, the output of said rectifier circuit varying in sign and magnitude with the D. C. input signal.

6. An electrical control circuit comprising a D. C. signal input circuit having two sets of output terminals and operable to produce at each set of output terminals a direct current which at zero signal is equal at both sets of terminals and is above zero in magnitude, and upon increase in signal magnitude increases in magnitude at one set of terminals and decreases correspondingly at the other set of terminals, increase or decrease of the output current at a set of terminals being dependent upon the sign of the signal, a saturable reactor circuit comprising a pair of saturable reactors each having a pair of A. C. coils and a D. C. coil wound on a common core, the A. C. coils being so arranged as not to induce an A. C. voltage in the associated D. C. coil and said D. C. coils being connected one to each set of output terminals of said input circuit, and a supply circuit for an A. C. load adapted for connection to a source of alternating current, the A. C. coils of said reactors being connected in the supply circuit to form with the load separate circuits each including the A. C. coils of one reactor reversely connecting the load in said supply circuit, a full wave rectifier circuit connected to form the load for said supply circuit, the output of said rectifier circuit varying in sign and magnitude with the D. C. input signal, and a negative feed-back from said rectifier circuit to said input circuit.

7. In an electrical control circuit, an A. C. signal input circuit having two sets of output terminals and operable to produce at each set of output terminals a direct current which at zero signal is equal at both sets of terminals and is above zero in magnitude and upon increase in signal magnitude increases in magnitude at one set of terminals and decreases correspondingly at the other set of terminals, increase or decrease of the output current at a set of terminals being dependent upon the sign of the signal, and a saturable reactor circuit comprising a pair of saturable reactors each having an A. C. coil and a D. C. coil, said D. C. coils being connected one to each set of output terminals of said input circuit, and a supply circuit for an A. C. load adapted for connection to a source of alternating current, the A. C. coils of said reactors being connected in the supply circuit to produce in a load connected to the supply circuit an alternating current varying in sign and magnitude with the input signal.

8. In an electrical control circuit, an A. C. signal input circuit having two sets of output terminals and operable to produce at each set of output terminals a direct current which at zero signal is equal at both sets of terminals and is above zero in magnitude and upon increase in signal magnitude increases in magnitude at one set of terminals and decreases correspondingly at the other set of terminals, increase or decrease of the output current at a set of terminals being dependent upon the sign of the signal, and a saturable reactor circuit comprising a pair of saturable reactors each having a pair of A. C. coils and a D. C. coil wound on a common core, the A. C. coils being so arranged as not to induce an A. C. voltage in the associated D. C. coil and said D. C. coils being connected one to each set of output terminals of said input circuit, and a supply circuit for an A. C. load adapted for connection to a source of alternating current, the A. C. coils of said reactors being connected in the supply circuit to form with the load separate circuits each including the A. C.

coils of one reactor reversely connecting the load in said supply circuit.

9. In an electrical control circuit, an A. C. signal input circuit having two sets of output terminals and operable to produce at each set of output terminals a direct current which at zero signal is equal at both sets of terminals and is above zero in magnitude and upon increase in signal magnitude increases in magnitude at one set of terminals and decreases correspondingly at the other set of terminals, increase or decrease of the output current at a set of terminals being dependent upon the sign of the signal, a saturable reactor circuit comprising a pair of saturable reactors each having a pair of A. C. coils and a D. C. coil wound on a common core, the A. C. coils being so arranged as not to induce an A. C. voltage in the associated D. C. coil and said D. C. coils being connected one to each set of output terminals of said input circuit, and a supply circuit for an A. C. load adapted for connection to a source of alternating current, the A. C. coils of said reactors being connected in the supply circuit to form with the load separate circuits each including the A. C. coils of one reactor reversely connecting the load in said supply circuit, and a negative feed-back from the output of said saturable reactor circuit to said signal input circuit.
10. An electrical control circuit comprising an A. C. signal input circuit having two sets of output terminals and operable to produce at each set of output terminals a direct current which at zero signal is equal at both sets of terminals and is above zero in magnitude and upon increase in signal magnitude increases in magnitude at one set of terminals and decreases correspondingly at the other set of terminals, increase or decrease of the output current at a set of terminals being dependent upon the sign of the signal, a saturable reactor circuit comprising a pair of saturable reactors each having a pair of A. C. coils and a D. C. coil wound on a common core, the A. C. coils being so arranged as not to induce an A. C. voltage in the associated D. C. coil and said D. C. coils being connected one to each set of output terminals of said input circuit, and a supply circuit for an A. C. load adapted for connection to a source of alternating current, the A. C. coils of said reactors being connected in the supply circuit to form with the load separate circuits each including the A. C. coils of one reactor reversely connecting the load in said supply circuit, and a full wave rectifier circuit connected to form the load for said supply circuit, the D. C. output of said rectifier circuit varying in sign and magnitude with the sign and magnitude of the A. C. input signal.
11. An electrical control circuit comprising an A. C. signal input circuit having two sets of output terminals and operable to produce at each set of output terminals a direct current which at zero signal is equal at both sets of terminals and is above zero in magnitude and upon increase in signal magnitude increases in magnitude at one set of terminals and decreases correspondingly at the other set of terminals, increase or decrease of the output current at a set of terminals being dependent upon the sign of the signal, a saturable reactor circuit comprising a pair of saturable reactors each having a pair of A. C. windings and a D. C. winding wound on a common core, the A. C. windings being so arranged as not to induce an A. C. voltage in the associated D. C. winding and said D. C. windings

being connected one to each set of output terminals of said input circuit, and a supply circuit for an A. C. load adapted for connection to a source of alternating current, the A. C. coils of each reactor being connected in the supply circuit to function in series with each other and with a load connected in the supply circuit and in effect in parallel with the A. C. coils of the other of said reactors, and a rectifier circuit comprising an inductive coupling having a primary winding connected as the load in said supply circuit and a center-tapped secondary winding, two pairs of grid controlled, gaseous electron tubes, one pair of said tubes having its plates connected to the ends of said secondary winding and its cathodes connected to the center-tap on said secondary and the other pair having its plates connected to the center-tap and its cathodes connected to the ends of said secondary winding, and means providing grid voltages for said tubes keeping the grid voltages of one pair of tubes in phase and the grid voltages of the other pair of tubes in counter-phase with their respective plate voltages.

12. An electrical control circuit comprising an A. C. signal input circuit comprising a pair of grid controlled electron tubes each having a plate, a cathode and a grid, a plate circuit for each of said tubes including a common A. C. source of plate potential and an inductively coupled signal input means having a primary winding adapted for series connection with a signal source and a secondary winding connected at its ends to the grids of said tubes and at its midpoint to the cathodes of said tubes to complete grid circuits for said tubes, said tubes being biased to have current and equal current flowing therein at zero signal magnitude, a saturable reactor circuit comprising a pair of saturable reactors each having a pair of A. C. windings and a D. C. winding wound on a common core, the A. C.

windings being so arranged as not to induce an A. C. voltage in the associated D. C. winding and said D. C. windings being electrically associated one with the plate circuit of each of said tubes, and a supply circuit for an A. C. load adapted for connection to a source of alternating current, the A. C. coils of each reactor being connected in the supply circuit to function in series with each other and with a load connected in the supply circuit and in effect in parallel with the A. C. coils of the other reactor, and a rectifier circuit comprising an inductive coupling having a primary winding connected as the load in said supply circuit and a center-tapped secondary winding, two pairs of grid controlled, gaseous electron tubes, one pair of said tubes having its plates connected to the ends of said secondary winding and its cathodes connected to the center-tap on said secondary and the other pair having its plates connected to the center-tap and its cathodes connected to the ends of said secondary winding, and means providing grid voltages for said tubes keeping the grid voltages of one pair of tubes in phase and the grid voltages of the other pair of tubes in counterphase with their respective plate voltages.

PAUL GLASS.
